UNITED STATES PATENT OFFICE.

CONRAD J. KILIAN, OF MILWAUKEE, WISCONSIN, ASSIGNOR OF ONE-HALF
TO DUSTIN ATWOOD, OF SAME PLACE.

SUPPORT FOR ELECTRIC-RAILWAY CONDUCTORS.

SPECIFICATION forming part of Letters Patent No. 425,101, dated April 8, 1890.

Application filed December 21, 1889. Serial No. 334,561. (No model.)

To all whom it may concern.

Be it known that I, CONRAD J. KILIAN, of Milwaukee, in the county of Milwaukee and State of Wisconsin, have invented certain new and useful Improvements in Supports for Electric-Railway Conductors; and I do hereby declare that the following is a full, clear, and exact description of the invention, which will enable others skilled in the art to 50 which it pertains to make and use the same, reference being had to the accompanying drawings, and to the letters of reference marked thereon, which form a part of this specification.

15 My invention relates to a brace or stay connecting the opposite posts used for sustaining the transmission-wires in electrical railways, and its object is to prevent the weight imposed upon the cross-wires from dragging 20 the posts inward and either bending or breaking them.

In the accompanying drawings, Figure 1 is an elevation showing two posts, the connecting cross-wire or sustaining-wire between them, and my improved arch or brace and its 25 connections. Figs. 2 and 3 show in detail the connections between my improved brace and the posts.

A A are the posts, preferably formed of 30 joints of iron pipe or single pieces of iron pipe, in order to gain the requisite strength without undue weight.

B is the cross-wire, connected in the usual way to the posts A A, and provided with proper 35 insulation.

C C are the transmission-wires, which serve to transmit the current to the motor machinery upon the car from a suitable source of power.

40 D is a connecting-beam, preferably arched, as shown, and by preference formed of a light T-rail of a shape in section shown at Fig. 2. The ends of this arched rail are inserted in blocks E E, formed of cast-iron or other suitable material, the lower ends of which are attached by insertion in the upper ends of the posts A, as shown in Figs. 2 and 3. If it is desired to attach these very strongly, the upper ends of the posts A may be provided with 45 an interior thread, into which the threaded ends of the blocks E may be screwed, and a

set-screw F may be employed to strongly connect the arched connecting-bar D and the blocks E E. From near the center of the arched bar D the depending wires G G are 55 used to sustain the wire B by being attached at their lower ends to the wires B B. I prefer to use for this purpose an eye in the covering-cap H, which serves to protect the joint of the transmitting-wires C C and to sustain 60 wire B. The wires G G may be provided with an interposed insulation, if desired.

The wires B and G G and the arched brace D form the cord, arc, and hangers of a truss, and the whole forms a very stiff and strong 65 connection between the posts A A and a powerful support for the transmitting-wires.

I is the slot for the reception of the end of the beam D.

Having thus described my invention, I 70 claim—

1. In an electric railway, the combination of the posts A A, a connecting brace or beam D, sustaining-wire B, hangers G G, and transmitting-wires C C, substantially as and for the 75 purposes set forth.

2. The combination of the posts A A, a sustaining-wire B, transmitting-wire C, a connecting-beam D, and hanger G, substantially as and for the purposes set forth. 80

3. In a support for overhead electric conductors, the combination of a rigid cross-brace and a pair of posts provided at or near their upper ends with blocks which have slots for the reception of the ends of said brace, substantially as and for the purposes set forth. 85

4. In a support for overhead electric conductors, the combination, with a rigid cross-brace, of a pair of posts provided with blocks having slots for the reception of the ends of said brace, and set-screws by which said brace is fastened in said blocks, substantially as and for the purposes set forth. 90

5. In a support for overhead electric conductors, the combination of a pair of posts, an arched brace and a cross wire or rod attached at the ends to said posts and connected at the intermediate point or points, and a hanger by which the electric conductor is suspended thereon, substantially as and for the purposes 100 set forth.

6. In a support for overhead electric con-

ductors, the combination of a pair of posts and an arched cross-brace and cross rod or wire attached at the ends to said posts and constituting a truss by which the posts are prevented from tipping toward each other and the conductor is suspended between them, and an intermediate connection between said cross-brace and wire or rod, by which they are prevented from spreading, substantially as and for the purposes set forth.

7. The combination, with a pair of posts, of a truss consisting of an arched cross-brace and

a cross wire or rod attached at the ends to said posts, and an electric conductor suspended from said truss by a suitable hanger, substantially as and for the purposes set forth. 15

In testimony that I claim the foregoing as my own I affix my signature in presence of two witnesses.

CONRAD J. KILIAN.
